UNITED STATES PATENT OFFICE.

ANDREW J. HARBISON, OF DREXEL, MISSOURI.

BRICK-CLEANING MACHINE.

1,332,038.

Specification of Letters Patent. Patented Feb. 24, 1920.

Application filed April 14, 1919. Serial No. 290,052.

To all whom it may concern:

Be it known that I, ANDREW J. HARBISON, a citizen of the United States, residing at Drexel, in the county of Cass and State of Missouri, have invented a certain new and useful Improvement in Brick-Cleaning Machines, of which the following is a specification.

My invention relates to improvements in brick cleaning machines.

The object of my invention is to provide a machine which will quickly, cheaply and efficiently clean old brick.

A further object of my invention is to provide a novel automatic brick cleaning machine, which is simple in construction, which can be cheaply made, which is durable and not liable to get out of order, and which may be operated to advantage by unskilled labor.

20 The novel features of my invention are hereinafter fully described and claimed.

In the accompanying drawings, which illustrate the preferred embodiment of my invention,

25 Figure 1 is a plan view of my improved brick cleaning machine.

Fig. 2 is a longitudinal vertical sectional view on the line 2—2 of Fig. 1.

Fig. 3 is a vertical cross section on the line 3—3 of Fig. 1.

Fig. 4 is a vertical sectional view on the line 4—4 of Fig. 1.

Fig. 5 is a vertical sectional view on the line 5—5 of Fig. 1.

35 Fig. 6 is a plan view, reduced, of a portion of the machine, some of the parts being omitted.

Fig. 7 is a cross section, reduced, on the line 3—3 of Fig. 1, some of the parts being omitted.

Similar reference characters designate similar parts in the different views.

The machine is preferably provided with a base comprising a platform 1 mounted in an elevated position upon vertical supporting members 2.

50 Mounted on the platform 1 is a right-angled plate having a horizontal portion 3 provided with a vertical hole 4, and a vertical portion 5 provided with a transverse hole 6, Figs. 2 and 3.

Mounted on the platform 1 in front of the vertical plate 5, that is to the right of said plate, as viewed in Figs. 1 and 2, is a supporting member comprising two vertical

standards 7 which are connected by a horizontal portion 8 comprising a table, upon which the bricks to be cleaned are automatically deposited, as hereinafter described, preparatory to being forced through the hole 6 for the purpose of being cleaned at their upper and lower sides and ends. 60

The bricks after being forced through the hole 6 are then forced downwardly through the hole 4, and a hole 9 in the platform 1 for the purpose of being cleaned at their longitudinal edges.

For forcing the bricks from the table 8 through the hole 6, I provide a horizontal longitudinally movable plunger 10, which is 70 adapted to rest upon a horizontal roller 11 revolvably mounted in the standards 7.

For reciprocating the plunger 10, it has pivoted to its front end, the rear end of a connecting bar 12, which is pivoted to a horizontal crank pin 13, the ends of which are rigidly secured in two disks 14, which are respectively rigidly secured to two horizontal shafts 15 and 16, which are respectively rotatably mounted in bearings 17 and 18 80 mounted on the platform 1. The shaft 16 has rigidly secured to it a pulley wheel 19, Fig. 1, which may be rotated by a suitable driving belt not shown.

For forcing the bricks downwardly 85 through the hole 4, I provide an upright plunger 20, which is reciprocated by means of a bell crank lever having one arm 21 pivoted by a transverse pin 22 to the upper end of the plunger 20, the other arm 23 of the bell crank lever being pivoted by a horizontal pin 24 mounted in a vertical hole 25 in the plunger 10.

The bell crank lever is pivoted at its angle by a horizontal pin 26 which has its ends respectively supported in the standards 7. For the purpose of cleaning the lower side of each brick, there is secured to the forward side of the plate 5 a vertical plate 27, the upper edge of which is slightly above the 100 lower edge of the hole 6. The plate 27 has secured to its forward side a U-shaped plate having forwardly extending arms 28, the upper edges of which curve upwardly and rearwardly for the purpose of cutting the mortar 105 on the lower side of each brick, and for centering the brick with reference to the opening 6.

For cleaning the upper side of the brick, I provide a vertical plate 29 which is slid- 110

able vertically on the front side of the plate 5, and which has secured to its forward side a U-shaped plate 30 having two forwardly extending arms 31 which curve downwardly and rearwardly for the purpose of cutting the mortar and centering the brick with reference to the hole 6. The plates 29 and 30 are provided each with two vertical slots 32, Fig. 3 through which extend respectively two horizontal bolts 33 provided with nuts 34 for retaining the plate 29 against the plate 5.

Two levers 35 are pivoted to the forward side of the plate 5 by horizontal bolts 36 respectively and bear at their inner ends against the upper edge of the plate 29. The outer ends of the levers 35 are supported respectively by two vertical coil springs 37, which are respectively supported by two brackets 38 secured to the front side of the plate 5. The plate 29 scrapes the mortar off from the top side of each brick as it is forced through the hole 6 by the plunger 10. In case of a brick being thicker than normal, the plate 29 and the plate 30 will be forced upwardly against the pressure of the springs 37.

Secured to the forward side of the plate 5 at opposite sides of the hole 6 are two plates 39 and 40 provided respectively with forwardly extending arms 41 and 42, which are adapted to cut the mortar on the ends of the bricks and to center said ends with respect to the hole 6.

For scraping the two longitudinal edges of each brick as it is forced downwardly through the holes 4 and 9, after passing through the hole 6, I provide two horizontal plates 43 and 44, disposed respectively at the forward and rear side of the hole 4 and projecting respectively over the adjacent longitudinal edges of said hole.

The plate 43 is rigidly secured to the top of the plate 3 by bolts 45 which extend through a U-shaped plate 46 having two upwardly extending arms 47, which curve upwardly and forwardly for cutting the mortar on the adjacent forward edge of the brick.

The plate 44 is longitudinally slidable toward and from the hole 4 and is held in position on the plate 3 by means of two bolts 48 which extend respectively through two slots 49, provided in the plate 44 and in a U-shaped plate 50, which is rigidly secured to the plate 44 and which is provided with two upwardly extending arms 51, the forward edges of which curve upwardly and rearwardly and which cut the mortar on the adjacent edge of the brick, and serve with the arms 47 to guide the brick through the hole 4.

The plate 44 and with it the plate 50 are normally yieldingly forced toward the hole 4 by means of two levers 52, which are pivoted on vertical pivot pins 53 respectively, mounted in the plate 3. The levers 52 have

their outer ends bearing against the rear edges of the plates 44 and 50, and their inner ends are respectively connected to one set of ends of two coil springs 54, which are respectively secured at their other set of ends to two pins 55, mounted vertically in the plate 3.

If a brick which is wider than the normal width is forced downwardly by the plunger 20 through the hole 4, the plates 44 and 50 are forced rearwardly against the tension of the springs 54.

The plunger 20 near its lower end is attached to the forward end of a flat spring 56, which extends forwardly and rearwardly and has its rear end rigidly secured to a block 57 mounted on the platform 1. The spring 56 serves to guide the lower end of the plunger 20.

For automatically and consecutively feeding bricks upon the table 8, while the plunger 10 is in the retracted position shown in Figs. 1 and 2 in solid lines, there is provided an endless chain belt 58, Figs. 1, 3 and 5, which is preferably disposed at right angles to the path of movement of the plunger 10, and which is mounted on two sprocket wheels 59 and 60, which are respectively rigidly secured to two horizontal shafts 61 and 62 which are respectively mounted in two sets of bearings 63 and 64 mounted on the platform 1.

Secured at intervals to the belt 58 are conveyer blades 65 which are adapted to propel bricks 66, one of which is shown in solid lines and one in dotted lines in Fig. 1 and which are carried by the chain belt 58 and are consecutively deposited on the table 8.

The upper portion of the belt 58, which carries the bricks 66 rests upon and travels along the top of an inverted channel support 67, the vertical flanges of which are supported upon and secured rigidly to the top of the platform 1.

The bricks 66 have their longitudinal edges guided between two horizontal spring plates 68 and 69, which, for the most part, are disposed parallel with the chain 58, and which are disposed respectively at opposite sides of said chain, as shown in Figs. 1 and 5.

The ends of the springs 68 and 69, which are distant from the table 8 are rigidly fastened to the channel support 67 by vertical pins 70. The ends of the springs 68 and 69 which are adjacent to the table 8 are free so as to permit the springs to be flexed laterally.

The chain 58 is driven by the shaft 62, which extends forwardly and is rotatably mounted adjacent to its forward end in a bearing 71, which is mounted upon the platform 1, Figs. 1 and 4. Secured rigidly to the forward end of the shaft 62 is a bevel gear wheel 72, which is engaged once dur-

ing each revolution of the disk 14 adjacent thereto by an arcuate row of gear teeth 73 on the outer side of said disk. The disposition of the teeth 73 is such that when the 5 plunger 10 is in the retracted position shown in solid lines in Figs. 1 and 2, with the crank pin 13 as shown in Figs. 1, 2 and 4, the teeth 73 will begin engagement with the bevel gear wheel 72, thereby rotating the 10 latter and the shaft 62 and driving the belt 58 in a direction such that the bricks 66 will be advanced and the foremost brick will be deposited upon the table 8 in front of the opening 6. The number of teeth 73 is such 15 that during each revolution of the disk 14 having the teeth 73, the travel of the belt 58 will cause a brick to be deposited upon the table 8.

When the brick has been deposited upon 20 the table 8 in front of the opening 6, the plunger 10 will have started on its forward movement and will engage the front edge of the brick and force the brick between the scraping plates 27 and 29 and through 25 the hole 6. The plates 27 and 29 will scrape the mortar off from the lower and upper sides of the brick, the arms 28, 31, 41 and 42 cutting into the mortar and serving to properly guide the brick between the scraping 30 plates 27 and 29.

After the brick has passed through the hole 6, it is forced between two spring plates 35 74 which are secured at their forward ends to the rear side of the plate 5, and which extend rearwardly from said plate over the hole 4 and at opposite sides respectively of the plunger 20. The springs 74 are sufficiently strong to enable them to support the brick until the plunger 20 descends and 40 forces it through the hole 4, which operation takes place as the plunger 10 is being retracted.

When the brick passes through the hole 4, it has its forward and rear edges scraped 45 by the plates 43 and 44. The ends of the brick are scraped clear of mortar by the plates 39 and 40 when the brick is passing between said plates and through the hole 6.

After the brick has passed through the 50 holes 4 and 9 its sides and edges will be cleaned of mortar and it will be ready to use. The bricks will be removed from below the platform 1 after being cleaned so as not to obstruct the cleaning operation on the bricks 55 which follow.

What I claim is:—

1. In a brick cleaning machine, the combination with two scraping devices, of means for consecutively forcing bricks between 60 said devices, an endless belt for consecutively depositing bricks into a position in which said forcing means can force the

bricks between said devices, and means for intermittently driving said belt.

2. In a brick cleaning machine, a combination with two devices for respectively scraping mortar from opposite surfaces of the brick, of a reciprocative plunger for forcing bricks consecutively between said devices, an endless belt having means for 65 consecutively depositing the bricks into a position in which the plunger can force the bricks between said devices, and joint means for driving said belt and reciprocating said plunger. 75

3. In a brick cleaning machine, the combination with means for cleaning mortar from the surface of a brick, including a reciprocative plunger for forcing the brick into operative relationship with said cleaning means, of a belt having means for consecutively feeding bricks into a position between said plunger and said cleaning means, and means for reciprocating said plunger and for intermittently driving said belt at 80 such times as the plunger is in the retracted position. 85

4. In a brick cleaning machine, the combination with means for removing mortar from the surfaces of a brick, of an endless belt having means for consecutively feeding bricks into operative relationship with said mortar removing means, and means for intermittently operating said belt. 90

5. In a brick cleaning machine, means for 95 scraping mortar from the surfaces of a brick, including two plungers for consecutively forcing bricks into operative relationship with said scraping means, a rotary driving member, an endless belt having means 100 for consecutively feeding bricks into operative relationship with said forcing means, and means actuated by said driving member for driving the belt and for operating said forcing means. 105

6. In a brick cleaning machine, means for removing mortar from a brick, including a scraping device and a reciprocative plunger for forcing the brick into operative relationship with the scraping device, a belt having 110 means for feeding bricks into a position between the plunger and said scraping device, a rotary member, means actuated by the rotary member for reciprocating said plunger, a rotary shaft, means actuated by said shaft 115 for driving said belt, the rotary member having a segmental arcuate row of teeth, and a gear wheel meshing with said teeth and adapted for intermittent engagement therewith and secured to and rotatable with 120 said shaft.

In testimony whereof I have signed my name to this specification.

ANDREW J. HARBISON.
